UNITED STATES PATENT OFFICE.

WILLIAM J. MOXLEY, OF CHICAGO, ILLINOIS.

DESIGN FOR A BUTTER OR OLEOMARGARIN BRICK OR PRINT.

SPECIFICATION forming part of Design No. 32,782, dated June 5, 1900.

Application filed May 11, 1900. Serial No. 16,372. Term of patent 14 years.

To all whom it may concern:

Be it known that I, WILLIAM J. MOXLEY, a citizen of the United States, residing at Chicago, Illinois, have invented and produced a new and useful Design for Butter or Oleomargarin Bricks or Prints, of which the following is a specification.

In the drawings, Figure 1 represents a plan view of a butter-print, and Fig. 2 represents a central sectional elevation of the same.

As shown in the drawings, the leading or important feature of my design consists in a butter or oleomargarin brick or print having on its upper or top surface two raised orna-

mental designs A, representing in effect the 15 fleur-de-lis, surrounded by a border of raised half balls or beads, dividing the brick into two panels, with one of the ornamental designs A in each.

What I regard as new, and desire to secure 20 by Letters Patent, is—

The design for a butter or oleomargarin print or brick herein shown and described.

WILLIAM J. MOXLEY.
